CLAIM

The ornamental design for a connector case for cable, as shown and described.

DESCRIPTION

1.1 is a perspective view of a connector case for cable showing our new design;

1.2 is a top plan view thereof;

1.3 is a front elevation thereof;

1.4 is a right side elevation view thereof;

1.5 is a left side elevation view thereof;

1.6 is a bottom view thereof;

1.7 is a rear elevation view thereof; and

1.8 is a perspective view thereof showing environment.

In Reproductions 1.1 through 1.7, the broken lines are for the purpose of illustrating portions of the connector case for cable that form no part of the claimed design. In Reproduction 1.8, the broken lines are for the purpose of showing both environment and portions of the article that form no part of the claimed design.
